LABORATORY TRAY FOR COOLING BIOLOGICAL SPECIMENS

Harry James Pappas, Hinsdale, Ill., assignor to Miles
Laboratories, Inc., Elkhart, Ind.

Filed Mar. 4, 1974, Ser. No. 447,486

Term of patent 14 years

Int. Cl. D24—02

U.S. Cl. D32—1 A

FIG. 1

FIG. 2

FIG. 3

FIG. 1 is a top perspective view of a laboratory tray for cooling biological specimens showing my new design; FIG. 2 is a side elevational view thereof taken along line 2—2 of FIG. 1; and the side opposite being a mirror image; and

FIG. 3 is an end elevational view thereof taken along line 3—3 of FIG. 1, the end opposite is similar with the plug omitted therefrom.

The bottom exterior is flat and unornamented.

I claim:

The ornamental design for a laboratory tray for cooling biological specimens, substantially as shown and described.
